UNITED STATES PATENT OFFICE.

DAVID L. KEELER, OF GRAND RAPIDS, MICHIGAN.

PITMAN FOR SEWING-MACHINES.

SPECIFICATION forming part of Letters Patent No. 314,249, dated March 24, 1885.

Application filed September 17, 1884. (No model.)

To all whom it may concern:

Be it known that I, DAVID L. KEELER, a citizen of the United States, residing at the city of Grand Rapids, in the county of Kent and State of Michigan, have invented certain new and useful Improvements in Sewing-Machines; and I do hereby declare the following to be a full, clear, and exact description of the invention, such as will enable others skilled in the art to which it appertains to make and use the same.

This invention relates to the pitman which connects the upper main shaft of a sewing-machine with the lower shaft of the same; and it consists in improved means for taking up the wear between the pitman and the roll-pin, and between the roll and wrist pins.

In the accompanying drawings, Figure 1 is a front view of a portion of a pitman constructed in accordance with my invention, showing also the wrist and roll pins. Fig. 2 is a side view of the same.

Like letters designate corresponding parts in all the figures.

The pitman A is constructed with a longitudinally-extending slot, B, in which plays the roll-pin C. This roll-pin embraces the wrist-pin D, and is made in two parts, a a, so that it may be tightened up to take up the wear which takes place between the roll and wrist pins. To provide for thus tightening up, and at the same time to provide for taking up the wear between the pitman and roll-

pin, the slot B of the pitman is at either end lengthened by means of a narrow V-shaped auxiliary slot, b. The pitman is provided with two tightening-screws, E E, which are located on the pitman so as to cross the auxiliary slots b b, and as the screws are tightened they contract the auxiliary slots b b, and with them the main slot B, thus compensating the wear between the pitman and roll-pin, and between the roll-pin and the wrist-pin. The roll-pin C is held in position on the wrist-pin D by means of a flanged head, e, formed on the two parts of the roll-pin, and by a nut, d, which screws onto the end of the wrist-pin.

I claim as my invention—

1. A pitman, A, provided with a slot, B, and with auxiliary slots b b, in combination with a roll-pin, C, which plays in the slot B, and adjusting-screws E E, which are adapted to contract the slots b b and B, and thereby take up the wear between the pitman and roll-pin, substantially as set forth.

2. The combination of the pitman A, provided with slots b b B, the roll-pin C, formed in two parts, a a, the wrist-pin D, and the adjusting-screws E E, substantially as and for the purpose set forth.

In testimony whereof I affix my signature in presence of two witnesses.

DAVID L. KEELER.
